United States Patent Office

Des. 226,740
Patented Apr. 17, 1973

226,740

HAIR DRYER

Norman A. Steinkamp, Chicago Heights, Ill., assignor to Sunbeam Corporation, Chicago, Ill.

Filed Dec. 29, 1971, Ser. No. 213,804

Term of patent 14 years

Int. Cl. D28—03

U.S. Cl. D86—10 F

FIG. 1 is a reduced perspective view of a hair dryer showing my new design;

FIG. 2 is a left side elevational view;

FIG. 3 is a bottom plan view;

FIG. 4 is a front elevational view;

FIG. 5 is a rear elevational view; and

FIG. 6 is a cross-sectional view taken along line 6-6 of FIG. 5.

I claim:

The ornamental design for a hair dryer, as shown.
